COMBINED TABLE AND CARRYING CASE FOR MODEL BUILDING OR SIMILAR ARTICLE

Benjamin F. Olson, 20 N. Compo Road,
Westport, Conn. 06880

Filed Jan. 6, 1969, Ser. No. 15,225

Term of patent 14 years

Int. Cl. D3—01

U.S. Cl. D87—1

FIG.1

FIG.2

FIG.3

FIG.4

FIG. 1 is a left side, top and front perspective view of a combined table and carrying case for model building or similar article, showing my new design in closed position;

FIG. 2 is a rear, top and left side perspective view in closed position;

FIG. 3 is a left side, top and front perspective view to an enlarged scale in open position; and

FIG. 4 is a left side, top and front perspective view to an enlarged scale in open position with the removable compartmented tray in a position closer to the worktable top of the case.

I claim:

The ornamental design for a combined table and carrying case for model building or similar article, as shown and described.
